UNITED STATES PATENT OFFICE

ARTHUR STOCKSTROM, OF ST. LOUIS, MISSOURI, ASSIGNOR TO AMERICAN STOVE COMPANY, OF ST. LOUIS, MISSOURI, A CORPORATION OF NEW JERSEY

DESIGN FOR A RANGE

Application filed October 6, 1930. Serial No. 37,159. Term of patent 14 years.

To all whom it may concern:

Be it known that I, ARTHUR STOCKSTROM, a citizen of the United States, residing in the city of St. Louis and State of Missouri, have invented a new, original, and ornamental Design for Ranges, which is a continuation in part of my two applications Serial No. D-32,910, filed September 26, 1929, and my application Serial No. D-32,911, filed October 2, 1929, both applications being for designs for ranges, of which the following is a specification, reference being had therein to the accompanying drawing.

In the accompanying drawing:

Figure 1 is a perspective view of a range showing my new design, with the swinging cover shown in an elevated position disclosing the open burner top portion.

Figure 2 is a perspective view of a range showing my new design with the swinging cover lowered to a horizontal position and concealing the open burner top portion.

I claim:

The ornamental design for a range, as shown.

In testimony whereof, I hereunto affix my signature.

ARTHUR STOCKSTROM.
